PENCIL WELL

Ira Saltz, Greenlawn, N.Y., assignor to Oxford
Pendaflex Corporation, Garden City, N.Y.

Filed Sept. 28, 1972, Ser. No. 295,986

Term of patent 14 years

Int. Cl. D19—02

U.S. Cl. D19—85

FIG. 1**FIG. 2****FIG. 4****FIG. 3****FIG. 5**FIG. 6

FIG. 7

FIG. 8

FIG. 9

FIG. 10

FIG. 1 is a perspective view of a pencil well showing my new design in a contrasting opaque and transparent form;

FIG. 2 is a front elevational view thereof;

FIG. 3 is a top plan view;

FIG. 4 is a side elevational view;

FIG. 5 is a bottom plan view;

FIG. 6 is a perspective view of a modified form of the pencil well, shown in opaque form;

FIG. 7 is a front elevational view thereof;

FIG. 8 is a side elevational view;

FIG. 9 is a top plan view; and

FIG. 10 is a bottom plan view.

I claim:

The ornamental design for a pencil well, as shown and described.
